Attorney

UNITED STATES PATENT OFFICE.

LOUIS KORN, OF HOUSTON, TEXAS.

COLLAPSIBLE CONTAINER.

Application filed April 3, 1925. Serial No. 20,499.

My invention relates to containers such as crates and boxes adapted to collapse into compact form for shipment or storage.

The principal object of my invention is to provide a crate, or box which is strong and simple in construction; and which may be readily collapsed, when desired, into compact form and greatly reduced size. It is desired to so construct the container that it may be locked in open position by means also serving to prevent entrance to the container. Other objects and advantages will appear in the detailed description which follows.

Referring to the drawing, Fig. 1 is a top plan view of a crate embodying my invention. Fig. 2 is a vertical section on the plane 2-2 of Fig. 1. Fig. 3 is a side elevation of the crate in collapsed condition. Fig. 4 is a transverse vertical section showing the use of a horizontal partition. Like numerals of reference are applied to like parts in all the views.

The invention is disclosed herein as applied to a crate, such as is commonly used to ship poultry. There is a lower floor 1, of board or the like, rectangular in shape, which forms a base for the attachment thereto of side walls 2 and 3 and end walls 4 and 5, which may be partly of coarsely woven wire mounted on a frame.

The side and end walls are adapted to be hinged to the base so as to be swung down parallel with the floor 1. To accomplish this, the side wall 3 is formed with a plurality of staples 6 driven into the lower side and extending inwardly to engage with staples 7, driven into the floor board 1. A hinge is thus formed which allows free movement of the side when it is to be swung down into the dotted line position shown in Fig. 4. The opposite side 2 is adapted to collapse above the side 3 and hence I provide a narrow strip 8 secured to the floor by nails or the like. It supports the side 2 spaced slightly up from the floor. The staples 6 and 7 forming the hinge for the side 2 are the same as on the opposite side, except that the staples 7 are longer, so as to reach from the floor to engage the staple 6 in the side.

The ends are hinged to the floor in the same manner as the sides, but as they must collapse above the sides, they are spaced above the floor by strips 9 and 10 and staples

11 are provided to engage the staples 6 in the ends, said staples 11 being long enough to reach the floor to which they are secured.

The side members are short enough to fit between the ends, as shown in Fig. 2, and dowel pins 13 in the ends at the sides thereof, are secured to the ends so as to fit within holes or recesses in the ends of the side members.

The top of the crate is formed of two pieces, a short piece 14 and a long piece 15, each of which is hinged to the adjacent end piece, as shown at 17. The longer piece 15 has secured thereon a cleat 16 projecting beyond its edge to overlap the adjacent edge of the shorter piece 14.

The longer piece is also formed with a small door 18 therein fitting in the frame at one side of the inner end and hinged thereto at 19. Its outer end has thereon a hasp 20, having an opening therein to engage a staple 21, which may project therethrough to receive a padlock. The two top pieces are provided with dowel pins 22 therein, to fit in openings in the side pieces. The longer piece 15 has a dowel only on the side thereof opposite the hasp 20. The staple 21 is secured to the inner side of the side piece 2 and extends upwardly through the edge of the top 15 thus also acting to hold the top in place as does the dowel on the opposite side.

In collapsing the crate the top pieces 14 and 15 are unlatched and raised, after which the end pieces are moved away from the side pieces to release the dowel pins 13. Then the side 3 is folded down on the bottom and the side 2 is afterward folded down on top of the other side as shown in dotted lines in Fig. 4. The ends with the top members attached thereto are then collapsed, the end 4 first and then the end 5. The parts will then be in position as shown in Fig. 3, the longer piece 15 of the top together with the adjacent end overlying the remaining parts.

While I have shown my invention as embodied in a poultry crate, it is obvious that it is applicable to many kinds of folding containers. Furthermore, it will be possible to provide a removable shelf or partition 23 which may be placed in the crate; a support therefor being provided by pins 24 extending through the sides or ends as shown in Fig. 4.

The advantages of this construction lie in its cheapness of construction; its strength and simplicity; and the efficient manner in which it collapses into compact form. The further advantages will be apparent to one skilled in the art without further description.

Having thus described my invention, what I claim as new and desire to protect by Letters Patent is:

1. A collapsible container comprising a bottom member forming a base, side members and end members hinged to said base, said members being each spaced a different distance above said base than the others, whereby they may fold down on said base one above the other, top members of unequal lengths hinged to said end members, means to secure said top and end members

detachably to said side members and means to lock them in position.

2. A collapsible container comprising a bottom member rectangular in shape, staples extending upwardly along the sides of said bottom, side and end members having inwardly projecting staples engaging the first-mentioned staples to form hinges, top members of unequal length hinged to said end members, a door in the longer of said top members, a hasp thereon, a staple in one of said side members extending through the longer top member and said hasp, and means on said longer top member to overlap and lock said shorter member.

In testimony whereof I hereunto affix my signature this 30th day of March, A. D. 1925.

LOUIS KORN.
